AUTOMOBILE TIE-DOWN HOOK

Larry Labell, Detroit, Mich., assignor to Vulcan Chain Corporation, Detroit, Mich.

Filed Aug. 11, 1965, Ser. No. 86,539

Term of patent 3½ years

(Cl. D54—11)

FIG. 1 is a perspective view of an automobile tie-down hook showing my design;

FIG. 2 is a side elevational view thereof; and

FIG. 3 is an end elevational view thereof.

The broken lines are for illustrative purposes only.

I claim:

The ornamental design for an automobile tie-down hook, substantially as shown and described.
